UNITED STATES PATENT OFFICE.

CHARLES D. JENNEY, OF INDIANAPOLIS, INDIANA, ASSIGNOR TO THE THOMSON-HOUSTON ELECTRIC COMPANY, OF CONNECTICUT.

AUTOMATIC REGULATOR FOR DYNAMOS.

SPECIFICATION forming part of Letters Patent No. 417,487, dated December 17, 1889.

Application filed June 11, 1888. Serial No. 276,734. (No model.)

To all whom it may concern:

Be it known that I, CHARLES D. JENNEY, a citizen of the United States, residing at Indianapolis, in the county of Marion and State 5 of Indiana, have invented certain new and useful Improvements in Automatic Regulators, of which the following is a specification.

The object of my said invention is to produce an automatic regulator for electric-light 10 machines, especially that class of dynamos used in incandescent lighting.

The leading feature of my present invention consists in the arrangement of continually-revolving wheels in such relation to properly-connected electro-magnets that when said magnets are energized said wheels will be operated as armatures, and thus drawn into engagement with a suitably-constructed clutch by which other mechanism is operated, and 15 20 a greater or less proportion of the resistance in a properly-connected rheostat thus cut into or out of the circuit.

My invention further consists in the construction and arrangement of certain parts of 25 this apparatus, as will be hereinafter more particularly described and claimed.

Referring to the accompanying drawings, which are made a part hereof, and on which similar letters of reference indicate similar 30 parts, Figure 1 is a front elevation of a regulator embodying my said invention; Fig. 2, a side elevation of the same; Fig. 3, a central vertical sectional view looking toward the right from the dotted line 3 3 in Fig. 1; Fig. 35 4, a top or plan view of the apparatus, but arranged somewhat differently, so that the controlling-magnet shall not be hidden by the other mechanism; Fig. 5, a horizontal sectional view, on an enlarged scale, looking upwardly from the dotted line 5 5 in Figs. 1, 2, and 3; Fig. 6, a diagram of electrical connections, illustrating the use of my improved apparatus when arranged for use with an incandescent-electric-light plant on the multiple or constant-potential system, (the apparatus being also shown as arranged for this system in the preceding figures of drawings;) and Fig. 7, a similar view to Fig. 6, except that the invention is shown in connection 40 45 50 with the series or constant-current system.

In said drawings, the portions marked A

represent a dynamo-electric machine; B, the outgoing line-wire; C, the incoming line-wire; D, a controlling-magnet set into a shunt-circuit; E *e*, contact-points with which the bar 55 carrying the armature of said magnet will under certain conditions come in contact; F F', the electro-magnets by which the revolving wheels are operated; G G', said revolving wheels; H, a hollow shaft carrying a worm 60 gear-wheel *i*, and mounted on the same shaft with said revolving wheels; I, a pivoted bar operated by said worm-gear and connected at one end to a wire running to the dynamo and adapted to come in contact with contact- 65 plates connected to the various resistance-coils at the other; J K, the wires by which the rheostat and the shunt-magnet of the dynamo field are connected in circuit.

The mechanical construction of the dynamo 70 and of many of the other parts may be any that is desired, and the description of such parts will therefore be brief.

In Fig. 6, which illustrates the principal features of the invention, the main lines are 75 shown running out, as usual, and a number of lamps are represented by small circles between two wires. The lines running to the lamps are in some cases shown as parted, indicating that these lamps are cut out. Branch 80 wires *b* and *c* run from the line-wires B and C to the magnet D, and the branch *b'* is also shown as connecting the branch wire *b* with the pivoted bar on which the armature D' to said magnet is mounted. A spring D² is 85 shown as connected to said bar on the other side, and when the potential between the mains is normal said bar is thus held equidistant between the contact-points E and *e*. When, however, the pressure becomes too 90 great and the magnet D thus energized beyond the capacity of the spring D² to resist, it draws the armature D' toward it, bringing the pivoted bar *d'* in contact with the contact-point E, and the current then flows by way of 95 the branch wire *b'*, said pivoted bar, said contact-point, and the wire E' to the electro-magnet F', which is thereby energized and draws the wheel G' toward it, bringing said wheel into engagement with the clutch *h'*, 100 and said clutch, being rigidly connected to the shaft H, revolves said shaft, and through

the worm-gear operates the bar I to cut in more resistance and restore the equality of electrical pressure upon the lines. When the pressure upon the lines becomes too weak, the 5 energy of the electro-magnet D decreases until the force of the spring D² draws the pivoted bar d' into contact with the contact-point e, when the current flows through said contact-point and the wire e' to the electro-magnet F, 10 which, being thus energized, draws the revolving wheel G, (which revolves in the opposite direction from the wheel G'), into contact with the clutch h, which, in similar manner as before described, operates the bar I, but 15 in the opposite direction, and cuts out enough of the resistance to equalize the electrical pressure. The current from the electro-magnets F and F' returns in either case over the wire e' to the branch wire c, and thence to the 20 main-line wire C. The resistance is kept in circuit by means of the wires J and K, as will be readily understood. As before stated, Figs. 1 to 5, inclusive, are illustrative of the apparatus as I have constructed it; but it is 25 obvious that the construction may be widely varied without departing from my invention. The circuits and course of the currents may also be varied in many ways, and I do not wish to limit myself in such matters to any 30 particular construction or arrangement. There are some features in the construction, however, which I regard as of importance and will now proceed to describe in detail.

The electro-magnets F and F', as before 35 stated, are so arranged that when energized they will exert an attracting force upon the wheels G and G', which are loosely mounted upon their shaft, and are thus capable of being drawn toward the poles f and f' of said 40 electro-magnets. Referring now particularly to Fig. 5, it will be noticed that the wheels G and G', while loosely mounted upon the shaft H, are connected through the parts g and g' with coiled springs g², secured in longitudinal cavities formed in the ends of said shaft, and are thus held away from the 45 clutches h and h' until the force of said coiled springs is overcome by the attraction of the magnets. When, however, the magnets are 50 energized and said spring force thus overcome, the wheels are moved slightly until the studs g³ thereon are brought into contact with the corresponding studs h² on said 55 clutches. Said clutches being secured fixedly on the shaft H, said shaft is thus revolved, and through the worm-gear operates the bar I, as before described and as will be readily 60 understood. The wheels G are kept in continual rotation by means of the belt G², which passes around one, then over the idle-wheel G³, and thence around the other, which has the effect to keep said wheels G and G' revolving in opposite directions at all times,

whether in engagement with the clutch-bars or not.

Of course the magnets might be arranged to repel instead of attract the wheels with the same result, and said wheels might be caused to revolve by a different means than a belt—such as a motor—without varying the invention essentially.

Having thus fully described my said invention, what I claim as new, and desire to secure by Letters Patent, is—

1. The combination, in an automatic regulator, of electro-magnets set into a circuit and loosely-mounted revolving operating-wheels set near the poles of said magnets, (which are also armatures for said magnets,) whereby, when one of said magnets is energized, a 75 wheel will be forced toward or from said magnet, and the mechanism for cutting the resistance in or out thus operated.

2. The combination of a revolving wheel mounted loosely upon a shaft, a spring by 85 which said wheel is normally held in a certain location on said shaft, a clutch part fixedly attached to said shaft, and an electro-magnet by which, when energized, said wheel (which is also the armature for said electro-magnet) will be drawn into engagement with 90 said clutch part, and said shaft thus caused to revolve with said wheel, substantially as set forth.

3. The combination, in an automatic regulator, of the operating-wheels G and G', the idle-wheel G³, the single belt G², arranged to drive all of said wheels, the clutch-bars h and h', the shaft H, the worm-gear, and a bar by 95 which the resistance is controlled operated by said gear, substantially as set forth.

4. The combination, in an automatic regulator, with the resistance-coils, and mechanism for operating the bar by which the amount of resistance is determined, of two wheels 105 loosely revolving in opposite directions upon the same shaft, two clutch-bars fixedly secured to said shaft alongside said wheels, and two electro-magnets the poles of which are arranged near to said wheels, whereby, when one of said electro-magnets is energized, one of said wheels will be forced by said magnet into engagement with one of said clutches and said bar be moved in one direction, and when the other magnet is energized the other 110 of said wheels will be forced by said magnet into engagement with the other of said clutches, and said bar be thus moved in the other direction.

In witness whereof I have hereunto set my hand and seal, at Indianapolis, Indiana, this 4th day of June, A. D. 1888.

CHARLES D. JENNEY. [L. S.]
